UNITED STATES PATENT OFFICE.

CHARLES F. OSGOOD, OF CLAREMONT, NEW HAMPSHIRE, ASSIGNOR TO SULLIVAN MACHINERY COMPANY, A CORPORATION OF MASSACHUSETTS.

MINING MACHINE.

Application filed August 7, 1925, Serial No. 48,808. Renewed November 22, 1927.

My invention relates to mining machines of the continuous cutter type and more particularly to mining machines of the continuous cutter type adapted to be fed laterally 5 relatively to the coal face to cut a kerf thereunder.

The primary object of my invention is to provide an improved mining machine wherein but a single feed operating member is 10 utilized to feed the machine and to control its angular relation with respect to the face of the coal. Another object of my invention is the provision of improved feeding mechanism for a mining machine. More particularly 15 it is an object of the invention to provide improved feeding mechanism for such a machine wherein a feed operating member may be driven in either direction at either a feeding or a cutting speed. A further object 20 of the invention is to provide improved actuating means for a feed operating member arranged midway between the sides of the mining machine frame wherein, due to the location of the elements of the driving trains, 25 great compactness may be secured. Other objects and advantages of the invention will hereinafter appear.

In a preferred form the invention may comprise a main frame slidable on its bottom 30 on the mine bottom and having mounted thereon a projecting cutter chain carrying cutter bar. The machine may be propelled both during cutting and at other times preferably by a single continuous flexible feed- 35 ing member secured at its free ends at the advancing and receding sides of the machine, respectively, and with which a single rotatable feed operating member cooperates in effecting feeding and controlling movement 40 of the machine. A single motor preferably supplies power both to the cutting and feeding mechanisms and is mounted on the main frame at the forward end of the latter in a position overlying the rear end of the cutter 45 bar. Power may be transmitted from the motor to the cutting and feeding mechanisms by means including a pinion on the rear end of the armature shaft and an improved variable speed transmission mechanism. Preferably 50 the transmission mechanism comprises a plurality of driving members rotating at different speeds, pairs of driven members actuated by said driving members at different speeds, means for causing any one of said driven members to operate as a driving mem-

ber means including elements associated with members of each of said pairs and adapted to be driven thereby for selectively driving a feed operating member, and friction controlled transmission devices between 60 said elements and the feed operating member.

In the accompanying drawings I have shown for purposes of illustration two forms which my invention may assume in practice. 65

In these drawings,—

Fig. 1 is a plan view of a mining machine constructed in accordance with one embodiment of my invention.

Fig. 2 is a partial side elevational view of 70 the machine shown in Fig. 1.

Fig. 3 is a rear end elevational view of the machine shown in Fig. 1.

Fig. 4 is an enlarged transverse horizontal view partially in elevation taken substantially on line 4—4 of Fig. 9. 75

Fig. 5 is an enlarged detail sectional view of one of the feed controlling clutches.

Fig. 6 is a detail transverse vertical sectional view taken substantially on line 6—6 80 of Fig. 4.

Fig. 7 is a detail sectional view of the interlocking mechanism for the feed controlling clutches.

Fig. 8 is a slightly modified form of the 85 planetary gearing shown in Fig. 4.

Fig. 9 is a longitudinally extending central vertical sectional view, partially in elevation, taken substantially on line 9—9 of Fig. 4. 90

Fig. 10 is a partial plan view of a slightly modified form of structure wherein a feed drum is utilized.

Fig. 11 is a rear end elevational view of the machine shown in Fig. 10. 95

In the construction illustrated in Figs. 1 to 9 I have shown for the purposes of illustration a mining machine, generally designated 1, which is herein of the flexibly fed, continuous cutter room and pillar type slidable on the mine bottom and having a main frame 2 of generally rectangular shape presenting parallel plane surfaces 3 and 4 upon which the machine is adapted to be selectively supported, i. e. when the machine is 100 being utilized as an undercutter or inverted and utilized as an overcutter. The machine frame 2 comprises a bottom bed section 5, a motor section 6, and a feed and cutting mechanism carrying section 7, the sections 6 105 and 7 being supported by the sections 3 and 4. 110

and 7 being supported upon the bed section 5 and rigidly secured thereto in any approved manner. As shown, suitably rigidly secured within and projecting forwardly from the 5 bed section 5 is a rigid cutter bar 8 about the outer edges of which a cutter bit carrying cutter chain 9 is adapted to be circulated, the cutter chain being driven through transmission means hereinafter described from a 10 motor 10, herein of the reversible type, housed within the section 6. As illustrated, a frame section 11 is suitably secured to the rear end of the frame section 7 by which an improved feed operating member 12, herein 15 in the form of a chain sprocket, is carried and this sprocket is likewise driven from the motor 10 through improved transmission means hereinafter described. The sprocket 12 is rotatable on a horizontal longitudinally 20 extending axis lying in the central longitudinal vertical plane of the machine.

In describing the cutting mechanism and the transmission gearing therefor, which is substantially the same as that disclosed in a 25 pending application of one Morris P. Holmes, filed March 14, 1925, Ser. No. 15,615, it will herein be observed that the rear end of the longitudinally extending horizontal armature shaft 13 has suitably secured thereto a 30 spur motor pinion 14 (see Figs. 4 and 9). The pinion 14 is meshed with a spur gear 15 secured to a shaft 16 disposed parallel with the shaft 13 and journaled within suitable ball bearings 17 carried within a supporting 35 member or bracket 18 and suitably secured within the frame section 7. The rear end of the shaft 16 has suitably secured thereto a bevel pinion 19 which is meshed with a large bevel gear 20 secured, as by a key 21, 40 to a vertical coaxially disposed shaft 22. The lower end of the shaft 22 has suitably secured thereto a spur pinion 23 which is meshed with a large spur gear 24, the hub of which is keyed as at 25, to the lower end of a vertical 45 drive shaft 26, the shaft 26 being disposed in the rear of and parallel with the shaft 22. The hub of the gear 24 has journaled thereon a usual driving sprocket 27 which cooperates with the cutter chain 9 to drive the latter in 50 a well known manner. As illustrated, the cutter chain sprocket 27 is adapted to be connected in operative driving relation with the shaft 26 by means of a clutch shipper member 28 splined, as at 29, to the shaft 26 and which 55 shipper is provided at its lower end with clutch teeth 30 which are adapted to cooperate with clutch teeth 31 formed in the upper end of the sprocket 27. Furthermore, the shipper member 28 is provided with a peripheral groove 32 with which the arms of a 60 shipper yoke 33 are adapted to cooperate. The shipper yoke 33 is herein preferably secured to a transverse horizontal shaft 34 journaled at its ends within the walls of the 65 frame section 7 and having secured thereto

an upstanding slotted arm or crank 35. Co-operating with the slot in the crank 35 is an eccentric pin 36 secured to an operating shaft 37 by which an operating member or handle 38 is carried. From the foregoing 70 description it will be evident that when it is desired by the operator to connect the sprocket 27 in operative driving relation with the shaft 26 the operating member 38 is manipulated, causing the eccentric pin 36 to rotate the shaft 34 and consequently swing the shipper yoke about its pivot, thus moving the shipper member 28 longitudinally of the shaft 26 and the gears 30 and 31 into operative driving relation. 75

The improved feeding mechanism is adapted to effect actuation of the feed operating member 12 in opposite directions through suitable fast and slow speed gearing. First 80 considering the mechanism common to both feeds and the fast feed mechanism more specifically, it will be noted that the upstanding hub of the bevel gear 20 has keyed thereto, as at 40, a vertically disposed shaft 41 disposed coaxially with the shaft 22 and above the latter and this shaft 41 is journaled at its upper end within suitable ball bearings 42 carried by the machine frame. Moreover, suitably secured intermediate the ends of the shaft 41 is a fast speed worm 43 which is 85 meshed with worm gears 44 and 45 rotatable in opposite relation on longitudinally extending horizontal axes parallel with the axis of the feed operating member 12 and spaced equally at each side of the central vertical 90 longitudinal axis of the machine (see Fig. 4). The worm gears 44 and 45 each have secured thereto, as by studs 46, (see Fig. 5) hub portions 47 and 48, the former being journaled upon bearing sleeves 49 carried by longitudinally extending horizontal shafts 50 and 51 disposed coaxially with the axes of the worm gears 44 and 45, respectively. As 95 illustrated, the forward ends of the shafts 50 and 51 are journaled within suitable ball 100 bearings 52 carried by the machine frame while the rear ends of the shafts 50 and 51 are journaled within ball bearings 53 carried by annular retaining members 54 likewise suitably carried by the machine frame. Housed 105 within the worm gears 44 and 45 are friction disc clutches which each comprise a series of interleaved discs 55 and 56 (see Fig. 5) one set of which is secured to the worm gears while the other set is suitably secured to clutch sleeves 57 keyed, as at 58, to the shafts 50 and 51, respectively. Encircling the hubs 48 of the worm gears are cylindrical plane clutch operating members 59 which are provided with longitudinally extending fingers 60 which pass through apertures 61 formed in the worm gears 44 and 45 and which are 110 adapted to engage certain of the clutch discs 55 and 56. As illustrated the rear ends of the shafts 50 and 51 have suitably secured 115

thereto spur pinions 62 and 63, respectively, which are meshed with a larger spur gear 64 disposed on a longitudinally extending horizontal axis coaxial with the axis of the feed 5 operating member 12. The gear 64 is suitably secured to a shaft 65 suitably journaled in ball bearings 65^a supported by the machine frame and this shaft has formed thereon, at its rear end, a spur pinion 66. As shown, the 10 spur pinion 66 is meshed with planetary gears 67, which gears are meshed with an internal reaction gear 68 suitably journaled, as at 69, on the frame section 11. It will be observed that this internal gear 68 is circumferentially grooved, as at 70, to receive a 15 brake band 71. The brake band 71 is provided with suitable operating mechanism including a lever 72 with which a threaded applying member 73 is pivotally connected and 20 this latter member cooperates with a hand wheel nut 74 carried by the rear end of the machine frame. As illustrated, the planetary gears 67 are journaled on stub shafts 75 formed integral with a supporting member 25 76, the latter having secured thereto a shaft portion 77 disposed coaxial with the shaft 65 and with the feed operating member 12, this shaft portion being journaled in bearings 78 and 79 suitably carried by the detachable 30 frame section 11. It will herein be observed that the shaft 77 is provided with a reduced rear end portion 80 which has secured thereto, as by a key 81, the hub of a spur gear 82. Loosely journaled on the hub of the gear 82 is 35 a spur gear 83 having secured thereto, as by a key 84, the feed operating member 12. It will further be noted that the gears 82 and 83 are adapted to be connected in operative driving relation by means of a longitudinally reciprocable internal gear clutch 85 disposed 40 coaxially with the shaft 77. Furthermore, the clutch member 85 may be slid longitudinally into engagement with a truck driving member 86 indicated by dotted lines in Fig. 9 45 similar to that described in the pending Holmes application noted above. From the foregoing description it will be evident that when the clutch discs 55, 56 controlling the driving of the shafts 50, 51, respectively, 50 are selectively applied, power may be transmitted from the motor 10 through the armature shaft, the motor pinion 14, the spur gear 15, the bevel pinion 19, the bevel gear 20, spur pinion 23 carried by the lower end of the shaft 22, spur gear 24, shaft 26, worm 88, worm gears 89 or 90 through one or the other 55 of the shafts 50, 51 and one or the other of the pinions 62, 63, spur gear 64, pinion 66, planetary gears 67 which react on the internal reaction gear 68, shaft 77, and, when the clutch 85 is connected to the gears 82, 83, to the feed operating member 12 to drive the latter in one direction or the other at a slow or cutting speed. It will also be evident that by varying the application of the brake band 71 and by varying the pressure applied to the slow speed friction clutches any suitable variants of such speed may be obtained at the will of the operator. 60

Associated with the feed controlling fast and slow speed clutches for the feed operating member 12 are improved controlling means therefor whereby the clutches may be selectively applied, thus preventing simultaneous application of the clutches and resultant damage to the machine parts. Such means for each set of clutches for the gears 62, 63, 64, 66, 67, 82, 83, 85, 88, 89, 90, 120 125 130 135 140 145 150 155 160 165 170 175 180 185 190 195 200 205 210 215 220 225 230 235 240 245 in the above mentioned pending Holmes application, on hub members 95 and 96. The hub member 95 is held in non-rotative relation by a screw 97 with respect to a sleeve member 98 journaled at its ends within the machine frame while the hub member 96 is held in non-rotative relation by a screw 99 to a shaft 100 disposed within and coaxially with the sleeve 98, the latter and the shaft 100 being relatively rotatable. The sleeve 98 has secured thereto at its outer end an operating handle 101 while the shaft 100 has secured thereto an operating member 102, the latter being arranged contiguous to the handle 101. As illustrated, interposed between the handles 101, 102, respectively, is a bracket 103 secured to the machine frame and having a bore 104 within which an interlocking pin 105 is slidably arranged, the latter being held in position by a pin and slot connection 106. The adjacent surfaces of the handles 101, 102 are provided with notches 107, 108, respectively, adapted to receive the ends of the pin 105. It will herein be evident that when one of the handles 101, 102 is manipulated, the interlocking pin slides into contact with the other handle, thus preventing rotation of the latter until the first handle is again in its inoperative position. It will thus be evident that when one or the other of the handles 101, 102 is actuated, the clutches for one set of the fast and slow speed clutches may be selectively applied, thus rotating the feed operating member 12 in one direction at either a fast or a slow speed while if the other operating handle is actuated either of the other set of clutches may be applied and the feed operating member consequently driven at either a fast or a slow speed in an opposite direction.

Cooperating with the feed operating member 12 is a continuous flexible feeding member 109, herein in the form of a feed chain, relative to which the machine is adapted to move and which flexible feeding member presents advance and receding flexible feeding portions 110, and 111, respectively, having free ends which are adapted to be connected to fixed extraneous abutments. It will herein be noted that each side of the forward end of the machine frame 2 is provided with an adjustable swing arm 112 and disposed at either side of the rear end of the machine frame are guide sheaves 113 rotatable on transverse horizontal axes. It will further be noted that at each corner of the rear end of the machine frame are sets of coaxially disposed guide sprockets 114, 115 and 116, 117 journaled on vertical axes within projecting bosses 118 formed integral with the detachable frame section 11 and these guide sheaves are disposed in horizontal planes substantially tangential to the exterior periphery of the feed operating member 12. From the foregoing it will be seen that the advance

portion 110 of the feed chain 109 may be extended from the left hand rib, if the machine is cutting from right to left, around the front swing arm 112 and then rearwardly along the advancing side of the machine frame over the guide sheave 113 around the lower guide sprocket 115 upwardly around the feed operating member 12, the chain then passing rearwardly around the upper guide sheave 114 and transversely and laterally from the receding end of the machine to the right hand rib of the coal. It will herein be noted that when the machine is cutting from left to right the feed chain may be rearranged with respect to the guiding sprockets and the feed operating member and the controlling handles 101, 102 and 38 may be detached and transferred to the opposite side of the machine, it being understood that the cutter bits are turned in their respective links and the motor reversed at that time.

Under certain conditions it is desirable for the cutter bar to operate in a plane at a substantial distance above the bottom surface of the mine, for instance when it is desired to cut out a dirt or slate band between the seams of the coal. Under such conditions the machine is enabled without change to be bodily inverted, the upper plane surface 4 as shown in Fig. 2 being disposed upon the mine bottom at that time as clearly described in the pending Holmes application Ser. No. 15,615 mentioned above.

In the form of my invention shown in Figs. 10 and 11 it will herein be observed that the chain engaging feed operating member 12 has been removed from the shaft 77 and replaced by a rope winding drum 120 upon which a suitable continuous wire rope or cable 121 is adapted to be wound, this wire rope forming separate advance and receding feeding portions for the machine. It will also be observed that the guide sprockets at the front and rear end of the machine frame are replaced by suitable rolls or pulleys 122. This form of my machine operates substantially in the same manner as the feed chain form heretofore described with the exception that the drum 120 is in the form of a "snubbing post", the friction of the cable on the drum permitting the shortening and lengthening of the feeding portions.

In the operation of my improved mining machine it will herein be noted that the machine is transported in any suitable manner to the coal face herein preferably by a transport truck driven by the driving member 86 (see Fig. 9). One of the other of the flexible feeding portions 110, 111 is then extended to a stationary abutment or roof jack in advance of the machine and the desired feed controlling clutch is operated, rotating the feed operating member at either a fast or a slow speed in the desired direction, thus moving the mining machine along the mine bottom

relative to the flexible feeding portion in the usual manner. The receding flexible portion 111 is then connected adjacent the right hand rib of the coal, if the machine is cutting from 5 right to left, to a suitable jack or take-up device, while the advancing portion 110 is extended laterally from the front guide sheave 112 at the advancing side of the machine to a suitable jack or take-up device disposed adjacent 10 the face at the left hand rib of the coal. The cutter chain sprocket 27 is then connected in driving relation with the motor 10, thus causing the cutter chain 9 to be rapidly circulated about the cutter bar 8. The 15 friction clutch controlling the slow speed worm gear 90 is then applied and the machine is fed relative to the receding flexible portion 111 and the bar fed or sumped into the face of the coal at a slow or cutting speed. 20 Any suitable device may be employed for maintaining a predetermined length of the advancing portion 110 between the swing arm 112 and the anchor jack, for instance a device similar to that described in a pending 25 application of Morris P. Holmes, Ser. No. 608,558, filed Dec. 22, 1922. After the sumping cut has been made the friction clutch controlling the gear 90 is released and the friction clutch controlling the gear 89 is applied, 30 thus causing the machine to be fed relative to the advancing portion 110 of the chain to be wound in, consequently causing the forward end of the machine to be swung laterally and bringing the cutter bar to a point 35 substantially perpendicular to the face of the coal, it being understood that any suitable device may be utilized for controlling the slack of the receding portion 111 on the chain at that time, for instance a chain hook member 40 similar to that disclosed in a U. S. patent to Morris P. Holmes, No. 1,544,067, patented June 30, 1925. The machine is then fed transversely across the face relative to the advance portion 110 of the chain at a slow or 45 cutting speed by means of the feed operating member 12 under control of the slow speed clutch. If it is desired to angle the cutter bar during the transverse cut, the feed operating member 12 may be momentarily reversed 50 drawing in the receding portion 111 at the desired speed. At the end of the transverse cut the machine is angled and withdrawn from the face in a well known manner. After the cutting operation is completed 55 the machine may be moved over the mine bottom at a fast speed under control of one or the other of the clutches within the gears 44, 45, the feed operating member 12 drawing in either the advance portion 110 or the receding portion 111 of the chain at a 60 fast speed at that time.

The operation of the wire rope form of the machine shown in Figs. 10 and 11 is substantially the same as the chain form here-

tofore described with the exception that a 65 cable is utilized and the advance and receding portions of the cable are drawn in by a winding drum. The operation of both forms of my machine when utilized as an overcutter is substantially the same as the operation of the machine when used as an undercutter with the exception that the machine is bodily inverted with the cutter bar disposed at a substantial distance above the mine bottom. Other operations and advantages 70 75 of my invention will be clearly apparent to those skilled in the art.

While I have in this application specifically described two forms which my invention may assume in practice, it will be understood that these forms of the same are shown for purposes of illustration and that the invention may be modified and embodied in various other forms without departing from its spirit or the scope of the appended claims. 80

What I claim as new and desire to secure by Letters Patent is:

1. In a mining machine, a motor, and feeding means driven thereby comprising a plurality of worm gears rotatable on parallel axes, and a feed operating member adapted to be selectively driven by said gears and to cooperate directly with flexible feeding means to effect feeding. 90

2. In a mining machine, a motor, and feeding means driven thereby comprising a plurality of worm gears rotatable on parallel longitudinally extending horizontal axes, and a feed operating member adapted to be selectively driven by said gears and to cooperate directly with flexible feeding means to effect feeding. 95

3. In a mining machine, a motor, and feeding means driven thereby comprising a terminal transmission element and means operative while the motor rotates in the same direction to drive said element at a plurality of predetermined speeds and at each of said speeds in opposite directions, and a feed operating member adapted to cooperate directly with flexible feeding means and driven by said element rotatable on a longitudinally extending horizontal axis and having a truck driving member coaxial therewith. 100

4. In a mining machine, a motor, and feeding means driven thereby comprising a terminal transmission element adapted to be driven, while said motor rotates in the same direction, at a plurality of speeds and at each of said speeds in opposite directions, said element being rotatable on a longitudinally extending horizontal axis, and feed operating and truck driving members coaxial with and driven at will by said element, said feed operating member being adapted to cooperate directly with flexible feeding means. 115

5. In a mining machine, a motor, and feeding means driven thereby comprising a plu-

rality of worm gears rotatable on parallel axes and driving worms therefor, certain of said worm gears being coaxial, and a feed operating member adapted to cooperate directly with flexible feeding means and rotatable on an axis parallel with said worm gears and adapted to be selectively driven by said gears.

6. In a mining machine, a motor, and feeding means driven thereby comprising a plurality of speed varying clutches arranged on spaced parallel axes and adapted with said motor rotating in but one direction to drive a transmission element at different predetermined speeds in one direction, and a feed operating member adapted to cooperate directly with flexible feeding means and rotatable on an axis parallel with and between the axes of said clutches and driven thereby.

7. In a mining machine, a motor, and feeding means driven thereby comprising a plurality of clutches adapted with said motor rotating in but one direction to drive a terminal transmission element at different predetermined speeds in one direction, a plurality of clutches for driving said element at different predetermined speeds in an opposite direction, a terminal element, all of said clutches having their axes parallel to a single straight line and each arranged to transmit drive to said terminal element independently of all the others, and a feed operating member adapted to cooperate directly with flexible feeding means and rotatable on an axis parallel with the axes of said clutches and driven by said terminal element.

8. In a mining machine, a motor, and feeding means driven thereby comprising a plurality of worms, a frictionally controlled planetary gearing driven thereby and including a reaction gear which is stationary at maximum driving speed and has operator-controllable, releasable braking means, and a feed operating member driven by said gearing and adapted to cooperate directly with flexible feeding means.

9. In a mining machine, a motor, and feeding means driven thereby comprising a plurality of worms rotatable on vertical axes, a frictionally controlled planetary gearing driven thereby and including a reaction gear which is stationary at maximum driving speed and has operator-controllable, releasable braking means, and a feed operating member driven by said gearing and adapted to cooperate directly with flexible feeding means.

10. In a mining machine, a motor, and feeding means driven thereby comprising a frictionally controlled planetary gearing disposed on a horizontal longitudinally extending axis and including a reaction gear which is stationary at maximum driving speed and has operator-controllable, releasable breaking means, and a feed operating member disposed coaxially therewith and driven

thereby and adapted to cooperate directly with flexible feeding means.

11. In a mining machine, a motor, and feeding means driven by said motor comprising a terminal transmission element, four separate clutches each operative to drive said element while all the others are inoperative and respectively operative to drive the terminal transmission element at a predetermined speed in one direction, at a different predetermined speed in the same direction, at a predetermined speed in the opposite direction, and at a different predetermined speed in said opposite direction, a feed operating member adapted to cooperate directly with flexible feeding means, and a clutch for connecting said member and said element.

12. In a mining machine, motor, feeding means driven by said motor comprising a terminal transmission element, four separate clutches for driving the terminal transmission element, each being operative to effect drive of said element while all the others are inoperative, one of said clutches effecting drive of said element at a predetermined speed in one direction, another drive of said element at a different predetermined speed in the same direction, the third drive of said element at a predetermined speed in the opposite direction, and the fourth drive of said element at a different predetermined speed in said opposite direction, means for selectively connecting said clutches each by itself to drive said element, a feed operating member adapted to cooperate directly with flexible feeding means and driven by said element, and a truck driving member rotatable by said element.

13. In a mining machine, a motor, and feeding means driven by said motor comprising a terminal transmission element, four separate clutches for driving the terminal transmission element, each being operative to effect drive of said element while all the others are inoperative, one of said clutches effecting drive of said element at a predetermined speed in one direction, another drive of said element at a different predetermined speed in the same direction, the third drive of said element at a predetermined speed in the opposite direction, and the fourth drive of said element at a different predetermined speed in said opposite direction, means including interlocking mechanism for selectively connecting said clutches singly to said element, and a feed operating member adapted to cooperate directly with flexible feeding means and driven by said element.

14. In a mining machine, a horizontal motor having an armature shaft, and feeding means driven by the rear end of said shaft comprising a plurality of worm gears rotatable on parallel axes certain of said gears being coaxial, and a feed operating member adapted to cooperate directly with flexible feeding

means and rotatable on an axis parallel with the axis of said gears and adapted to be selectively driven thereby.

15. In a mining machine, a motor, and feeding means driven thereby comprising a transmission element adapted to be driven while said motor rotates in one direction at a plurality of predetermined speeds and in opposite directions at each speed, a frictionally controlled planetary gearing driven by said element, and a feed operating member driven by said gearing and adapted to cooperate directly with flexible feeding means.

16. In a mining machine, a motor, and feeding means driven thereby comprising worm gears rotatable on parallel axes, and a feed operating member adapted to cooperate directly with flexible feeding means to effect machine feeding and rotatable on an axis 20 parallel with said gears and intermediate the axes of the same.

17. In a mining machine, a motor, and feeding means driven thereby comprising a worm rotatable on a vertical axis, and a frictionally controlled planetary gearing driven thereby and disposed on a longitudinally extending horizontal axis, said planetary gearing including a reaction gear which is stationary at maximum driving speed and has operator-controllable, releasable braking means, and a feed operating member driven by said gearing and adapted to cooperate directly with flexible feeding means.

18. In a mining machine, a motor, and feeding means driven thereby comprising a worm rotatable on a vertical axis, and a friction controlled planetary gearing driven thereby and disposed on a longitudinally extending horizontal axis, said planetary gearing including a reaction gear which is stationary at maximum driving speed and has operator-controllable, releasable braking means, and a feed operating member adapted to cooperate directly with flexible feeding means and driven by said gearing and disposed on an axis coaxial therewith.

19. In a mining machine, a motor and a feeding means driven thereby including a plurality of worms whose axes lie in a common vertical plane, and a feed operating member adapted to cooperate directly with flexible feeding means and rotatable on an axis lying in the same vertical plane as the axes of said worms and selectively driven by said worms.

20. In a mining machine, a motor and feeding means therefor including a plurality of worms rotating on a plurality of vertical axes, and a feed operating member adapted to cooperate directly with flexible feeding means and rotating on an axis lying in the same vertical plane with the axes of said worms and selectively driven by said worms.

21. In a mining machine, a motor and feeding means driven thereby including a plural-

ity of worms whose axes lie in a common vertical plane, and a feed operating member adapted to cooperate directly with flexible feeding means and rotatable on a horizontal axis lying in the same vertical plane as the axes of said worms and selectively driven by said worms.

22. In a mining machine, a motor and feeding means therefor including a plurality of worms rotating on a plurality of vertical axes, and a feed operating member adapted to cooperate directly with flexible feeding means and rotating on a horizontal axis lying in the same vertical plane with the axes of said worms and selectively driven by said worms.

23. In a mining machine, a motor and feeding means driven thereby comprising a feed operating member rotatable on a longitudinally extending horizontal axis and adapted to cooperate directly with flexible feeding means, and driving means therefor, comprising a plurality of trains each having a terminal gear element individual thereto and which rotates oppositely to the other terminal gear element while said motor rotates in but one direction, and a driving gear element for said feed operating member engaged directly by each of said terminal gear elements, in meshing relation.

24. In a mining machine, a motor and feeding means driven thereby comprising a feed operating member rotatable on a longitudinally extending horizontal axis and adapted to cooperate directly with flexible feeding means, and driving means therefor comprising a plurality of plural speed transmission trains each having a terminal gear element individual thereto rotatable at a plurality of predetermined speeds and a driving gear element for said feed operating member engaged directly by each of said terminal elements in meshing relation.

25. In a mining machine, a motor and feeding means driven thereby comprising a feed operating member rotatable on a longitudinally extending horizontal axis and adapted to cooperate directly with flexible feeding means, and driving means therefor comprising a plurality of speed and direction changing transmission trains each having a terminal gear element individual thereto rotatable in opposite directions and at a plurality of speeds, and a driving gear element for said feed operating member engaged directly by each of said terminal elements in meshing relation.

26. In a mining machine, a machine frame slideable on its bottom on the mine bottom, a motor carried thereby, and machine feeding mechanism driven by said motor including a feed operating member adapted to cooperate with flexible feeding means, and plural speed driving means therefor including coaxial fast and slow speed worm gears rotatable on axes parallel with the axis of said feed operating

member and selectively operable to drive said feed operating member at fast and slow speeds.

27. In a mining machine, a machine frame 5
slidable on its bottom on the mine bottom, a
motor carried thereby, and machine feeding
mechanism driven by said motor including a
feed operating member adapted to cooperate
with flexible feeding means, and plural speed
10 driving means therefor including coaxial fast
and slow speed worm gears rotatable on axes
parallel with the axis of said feed operating
member and selectively operable to drive said
feed operating member at fast and slow
15 speeds, and worms rotating on parallel axes
and meshing with said worm gears.

28. In a mining machine, a machine frame
slidable on its bottom on the mine bottom, a
motor carried thereby, and machine feeding
20 mechanism driven by said motor including a
feed operating member adapted to cooperate
with flexible feeding means, and plural speed
driving means therefor including coaxial fast
and slow speed worm gears rotatable on axes
25 parallel with the axis of said feed operating
member and selectively operable to drive said
feed operating member at fast and slow
speeds, worms rotating on parallel axes and
meshing with said worm gears, and inter-
30 meshing gearing connecting said worms for
simultaneous rotation.

29. In a mining machine, a machine frame
slidable on its bottom on the mine bottom, a
motor carried thereby, and machine feeding
35 mechanism driven by said motor including a
feed operating member rotatable upon an
axis lying in the central longitudinal vertical
plane of the machine and adapted to cooperate
with flexible feeding means, and plural speed

driving means therefor including coaxial fast 40
and slow speed worm gears selectively oper-
able to drive said feed operating member at
fast and slow speeds.

30. In a mining machine, a machine frame
slidable on its bottom on the mine bottom, a
motor carried thereby, and machine feeding
mechanism driven by said motor including a
feed operating member rotatable upon an 45
axis lying in the central longitudinal verti-
cal plane of the machine and adapted to co-
operate with flexible feeding means, and
plural speed driving means therefor includ-
ing coaxial fast and slow speed worm gears
50 rotatable on axes parallel with the axis of
said feed operating member and selectively
operable to drive said feed operating mem-
ber at fast and slow speeds.

31. In a mining machine, a machine frame
slidable on its bottom on the mine bottom, a
motor carried thereby, and machine feeding
55 mechanism driven by said motor including a
feed operating member rotatable upon an axis
lying in the central longitudinal vertical
plane of the machine and adapted to cooperate
with flexible feeding means, and plural speed
60 driving means therefor including coaxial fast
and slow speed worm gears rotatable on axes
parallel with the axis of said feed operating
member, a driving element coaxial with said
worm gears and operatively connected to said
65 feed operating member, and friction clutches
coaxial with said worm gears and operative to
selectively connect said worm gears in opera-
tive driving relation with said driving ele-
ment to effect rotation of said feed operating
70 member at either a fast or a slow speed.

In testimony whereof I affix my signature.
CHARLES F. OSGOOD.

CERTIFICATE OF CORRECTION.

Patent No. 1,704,671.

Granted March 5, 1929, to

It is hereby certified that the Certificate of Correction issued April 9, 1929, was erroneously drawn as to the misspelled word "coperate" in claim 29, and that this Certificate should have read as follows: Page 8, line 38, claim 29, for the misspelled word "coperate" read "cooperate", that the said Certificate may conform to the records of the office.

Signed and sealed this 30th day of April, A. D. 1929.

(Seal)

**M. J. Moore,
Acting Commissioner of Patents.**
